Specification for Design.

Patented July 20, 1920.

Application filed May 16, 1919. Serial No. 297,707. Term of patent 7 years.

To all whom it may concern:

Be it known that I, HERBERT T. DICKINSON, a citizen of the United States, residing at the Kenmark Hotel, in the city and county of Denver and State of Colorado, have invented a certain new, original, and ornamental Design for an Emblem, Badge, or Button, of which the following is a specification, reference being had to the accompanying drawing, forming part thereof.

In the drawing, the figure is a face view of the emblem, badge or button.

Having thus described my invention, I claim:—

The ornamental design for an emblem, badge or button as shown.

HERBERT T. DICKINSON.
